H. E. HUBBARD.
METHOD OF MAKING CURVED PRINTING PLATES.
APPLICATION FILED AUG. 19, 1918.

Patented July 19, 1921.

UNITED STATES PATENT OFFICE.

HENRY E. HUBBARD, OF OAK PARK, ILLINOIS, ASSIGNOR TO ADDRESSOGRAPH COMPANY, OF CHICAGO, ILLINOIS, A CORPORATION OF ILLINOIS.

METHOD OF MAKING CURVED PRINTING-PLATES.

1,384,897.

Specification of Letters Patent. Patented July 19, 1921.

Original application filed March 8, 1915, Serial No. 12,817. Divided and this application filed August 19, 1918. Serial No. 250,601.

To all whom it may concern:

Be it known that I, HENRY E. HUBBARD, a citizen of the United States, residing at Oak Park, in the county of Cook and State of Illinois, have invented certain new and useful Improvements in Methods of Making Curved Printing-Plates, of which the following is a specification.

This invention relates to a method of making curved metal printing plates, the application being a division of my co-pending application, Serial No. 12,817, filed March 8, 1915, and patented August 20, 1918, No. 1,276,532.

It is the object of my invention to provide a method of making curved metal printing plates in a simple and efficient manner, the curving being effected without distorting the printing characters thereon.

Further objects and advantages of my invention will be apparent as it is better understood by reference to the following specification when read in connection with the accompanying drawing illustrating the preferred embodiment thereof, in which—

Figure 1 is view in perspective of a metal blank scored in a plurality of parallel lines as in the first step of my method;

Fig. 2 is a view in perspective of the same blank having a plurality of printing characters struck up from the body thereof;

Fig. 3 is a view in perspective of the plate after the curving operation.

Fig. 4 is an end elevation of the curved plate, and

Fig. 5 is a sectional view illustrating a portion of a suitable apparatus for curving the plates.

The use of printing plates having characters struck up from the body of a sheet metal blank has been a recent development of the printing art. Methods and means for striking up printing characters from sheet metal blanks have been perfected and are in commercial use. The "graphotype" is an example of a machine adapted for use in preparing such plates and reference is made to the patent to Duncan No. 955,116 dated April 12, 1910, which illustrates one type of such a machine.

Inasmuch as printing machines having cylindrical beds are among the most efficient known, it is desirable to provide a method of preparing curved printing plates of the character above described adapted to be mounted upon the cylindrical beds of such machines. Considerable difficulty has, however, been experienced in producing a satisfactory curved printing plate for the reason that it is desirable to strike up the printing characters before the plate is curved and during the curving operation the characters are liable to distortion. A further difficulty has been experienced in bending the plate to the desired curvature and applicant has devised the present method to overcome the various difficulties encountered.

Referring to Fig. 1 of the drawing, 5 indicates generally a blank sheet metal plate which is first prepared by scoring the surface thereof along a plurality of lines 6 extending longitudinally of the plate. The plate is then placed in a suitable machine, such as the "graphotype" which need not be here described, and lines of printing characters 7, (Fig. 2) are struck up from the surface of the plate between the lines of scoring. It is to be understood that the characters shown in Fig. 2 are merely illustrative and that normally the surface of the plate between the lines of scoring will be more or less filled with printing characters. When the above operations have been completed the flat printing plate is ready for the curving operation which may be carried out in any suitable machine although the structure illustrated in Fig. 5 is best adapted for the purpose.

Referring to Fig. 5, a bed 8 is provided with a convexly curved face 9, the radius of curvature being that to which the plate is to be bent, and the width of the bed being substantially equal to the width of the printing plate to be treated. A presser head 10 is provided with a platen 11 having a facing 12 of yielding or resilient material such as rubber. The presser head 10 may be brought into contiguous relation with the plate 5 on the bed 8 by suitable mechanism which need not be here described to force the resil-

ient facing between the lines of printing characters and into engagement with the printing plate 5. The plate is bent, along the scored lines 6 and without distorting the 5 printing characters 7, to the curvature of the bed 8, and when the pressure is withdrawn the plate is found to be permanently bent to the desired curvature.

It will be noted from an inspection of 10 Fig. 5 that during the pressing operation the printing plate is rigidly supported with its under side coöperating with the curved face 9 of the bed 8. The yielding or resilient facing 12 engages the printing surface of 15 the plate and presses downward between the printing characters so that the pressure is exerted evenly over the entire surface of the printing plate. Applying pressure in this way for the bending operation is believed to 20 be very desirable, if not essential, to do the work properly, and I find that thereby I am enabled to produce a perfectly curved plate without distortion of the printing characters and with a minimum of effort. This yielding 25 or resilient pressure permits the bending of the metal only at the score lines, while the faces of the characters are left flat and each face is disposed tangentially to an arc concentric with the center of curvature of the 30 plate so that clear and distinct impressions will be made by each printing character on the plate. In order to properly bend a printing plate so that all the type characters thereon will produce a clear and distinct 35 impression, it is necessary, as pointed out in my Patent No. 1,276,532, that the pressure be applied simultaneously throughout the entire surface of the plate, so that the plate will bend only at the score lines 40 and the intermediate portions thereof bearing printing characters will be maintained in their original condition. This result has been accomplished by employing the yielding or resilient facing which fills the cavities 45 in the type characters and the spaces between the characters in each line and between the lines to form a protection for the characters and permit the plate to bend only on the score lines.

50 Printing plates prepared in accordance with my method preserve the original flat face of the printing characters which are essential to accurate and satisfactory registration in printing machines. The curvature 55 of the plates being permanent and accurate, they may be readily fitted onto the printing cylinder where they closely engage without buckling or other distortion.

It will be apparent that I have devised a 60 novel series of steps in a method for making curved printing plates comprising scoring a sheet metal plate, striking up raised characters from the surface thereof and bending the plate to the desired curvature, the bend-

ing occurring at the lines of scoring. It will 65 be further apparent that the plate resulting from my method is superior in printing qualities to any plate heretofore suggested because the printing characters retain their original flat faces tangential to a circle concentric with the curvature of the plate. 70

Various changes may be made in the steps of the method, as above defined, as well as in the apparatus used, without departing from the spirit and scope of the invention or sacrificing any of its material advantages, the outline hereinbefore recited being merely the preferred embodiment of the invention. 75

I claim:

1. The method of making curved printing 80 plates which consists of striking up printing characters on one face of a plate and then subjecting the plate to pressure between concavo-convex surfaces, the surface contacting with said characters being of resilient ma- 85 terial.

2. The step in the formation of a printing plate having a plurality of printing faces angularly disposed with relation to each other, which consists in scoring the plate on 90 a plurality of parallel lines and compressing the plate between concentrically curved surfaces adapted to be used irrespective of the number of printing faces to be produced on the plate. 95

3. A method of making curved printing plates which comprises scoring the plate on one side thereof in a plurality of parallel lines, striking up printing characters from the plate between said score lines, and then 100 applying yielding pressure to the plate and at the same time forcing a resilient facing against the type side of the plate and into the cavities of the type characters and into the spaces between the type characters to 105 preserve the type characters from distortion and permit the plate to be bent only along the score lines.

4. The method of forming a curved printing plate having a plurality of flat printing 110 faces, which is characterized by the use of concavo-convex surfaces between which the plate is compressed and which are adapted for all plates bent to the same radius irrespective of the number or size of the print- 115 ing faces of the finished plate.

5. The method of making curved printing plates which includes scoring a plurality of parallel lines on one side of the plate, striking up printing characters on the same side 120 of the plate between said score lines and then applying pressure through a curved body to the back of the plate and at the same time applying pressure through a concentrically curved body having a resilient face present- 125 ed to the top side of the plate.

6. The method of making a curved printing plate which consists in scoring the plate

on one face thereof and on a plurality of parallel lines, striking up printing characters on said face between said score lines and then subjecting the plate to pressure between 5 concentrically curved surfaces, the surface contacting with said face being of resilient material and the pressure applied to said

plate being sufficient to bend it along the score lines only.

HENRY E. HUBBARD.
